UNITED STATES PATENT OFFICE.

GEORGE L. SMITH, OF FORT WAYNE, INDIANA, ASSIGNEE TO THE SMITH CHIMES CLOCK COMPANY, A CORPORATION OF INDIANA.

CHIMES-STRIKING MECHANISM.

Application filed November 23, 1921. Serial No. 517,191.

To all whom it may concern:

Be it known that I, GEORGE L. SMITH, a citizen of the United States of America, and resident of Fort Wayne, in the county of Allen and State of Indiana, have invented certain new and useful Improvements in Chimes-Striking Mechanism, of which the following is a specification.

This invention relates to improvements in chimes striking mechanism, and the object thereof is to provide apparatus adapted to be periodically operated and which will, during its operation, strike a chime member or similar object a series of blows in timed sequence as in tolling, or, which will strike a series of chime members selectively in such chronological order and meter as may be predetermined to effect a melody.

The object of the invention is accomplished by the construction illustrated in the accompanying drawings in which:—

Fig. 1 is a front elevation of the apparatus, there being parts broken away, and certain electrical connections being shown in diagrammatical form;

Fig. 2 is a detail view showing an end elevation of one of the electrical make and break rotors for controlling the motor;

Fig. 3 is a similar view of another electrical make and break rotor for controlling the auxiliary apparatus;

Fig. 4 is an end elevation of the apparatus, the motor being omitted; and

Fig. 5 is a plan view of the apparatus, there being a portion broken away.

The characters appearing in the description refer to parts shown in the drawings and designated thereon by corresponding characters:—

The invention comprises a base 1 having standards 2 fixed thereon and in which is mounted a main shaft 3 that is adapted to have both rotary and longitudinal reciprocating movement in the standards 2. The

shaft 3 has in connection with one of its ends a swivel head 4 provided with a cross bar 5, and the adjacent standard 2 has bearing relation with another cross bar 6 that has a connection at each end with the corresponding end of the cross bar 5 by means of a spring 7 and adjusting screw 8, the springs exerting a force tending to cause the shaft 3 to move lengthwise in the standards 2 in the direction of its end opposite the swivel head.

The main shaft 3 has fixed thereon a gear

wheel 9 that has driven relation with a wide faced pinion 10, which is mounted upon an intermediate shaft 11, the latter being mounted in a pair of standards 12, and the intermediate shaft has fixed thereon a worm 60 wheel 13 that has driven relation with a worm 14 on a drive shaft 15 which is connected with an electrical motor 16 to be rotated thereby.

Mounted loosely upon the main shaft 3 is 65 a gear wheel 17 upon the hub 18 of which is arranged a projecting roller 19, and fixed concentrically upon the main shaft 3 is a barrel 20, one end of which is shaped to form a spiral cam 21 that bears against the roller 19. The gear wheel 17 has driven relation with another gear wheel 22 that is fixed on a countershaft 23 which is mounted in standards 24 on the base, and the countershaft 23 also has fixed thereon a back gear 25 having 70 driven relation with a wide faced pinion 26 that is fixed on the main shaft 3, so that as the main shaft rotates, the gear 17 will also be rotated through the medium of the back gear 25, countershaft 23 and the gear wheel 26 75 22, the same being so proportioned that the velocity of the main shaft exceeds that of the gear wheel 17 and consequently the cam 21 bearing against the roller 19 has progressive movement in relation therewith in the 80 direction of rotation. Also, the main shaft 3 is caused to move endwise toward the swivel head 4 during the progressive movement of the cam on the roller 19, except during the period when the offset 27 in the cam over- 85 takes the roller 19 and permits the main shaft upon which the cam is mounted to return in the opposite direction under the influence of the tension device comprising the 90 spring actuated swivel head. The pinion 10 95 on the intermediate shaft and the pinion 26 on the main shaft are of sufficient breadth as to remain in mesh respectively with the gear wheel 9 and the gear wheel 25 throughout the endwise reciprocal movements of the 100 main shaft 3.

Upon the main shaft 3 are fixed a series of drums 28, each of which has a series of projecting lugs 29 thereon arranged in a spiral path, and in juxtaposition with said 105 drums are arranged a corresponding series of trip hammers 30, each of which has operative relation with the corresponding drum, the lugs thereon having engagement in successive order with the hammer as the drum 110

revolves and moves lengthwise. Each hammer 30 is mounted in a corresponding post 31, and the shank 32 of the hammer normally rests against an adjustable stop 33 under the tension of a spring 34 which is connected with the hammer.

The stops 33 are mounted in a universal bar 35 that receives support from a series of posts 36 fixed upon the base, and a chime member 37 is suspended in front of each hammer in position to receive the impact of the hammer as it is actuated, thus, the chime members are caused to give forth sound, and it is the intention that the various chime members shall be such as to differ from each other in tone so that as the various hammers are actuated the corresponding chime members will be sounded accordingly and a melody effected.

In the operation of the mechanism, as the main shaft rotates the cam face 21 progresses on the roller 19 causing gradual endwise movement of the shaft. Thus, the drums on the shaft have longitudinal and rotary movement, and the projecting lugs are brought in succession into operable engagement with the corresponding hammers. By this arrangement each lug upon passing from engagement with the corresponding hammer is carried out of the way of the hammer so as to clear it upon succeeding revolutions until the drums are restored to their initial positions by the return endwise movement of the shaft.

As a means of controlling the chimes striking apparatus, the motor 16 is connected up with a source of energy 38 by means of conductors 39 and 40. The conductor 39 has connection between the motor and source of energy with a make and break device comprising a drum 41 mounted on the countershaft 23 and provided with flanges 42 and 43, the latter having a notch 44 therein. A pair of contact springs 45 and 46 mounted respectively on posts 47 and 48, and having engagement with the corresponding flanges 42 and 43, are connected with the conductor 39 so that the current for the motor passes normally through the drum, and the circuit therethrough is broken when the spring 46 enters the notch 44 in the flange 43.

Also, the conductor 39 has a shunt connection 49 including a switch 50 for same through which current may be supplied from the source of energy to the motor irrespective of the make and break device. The branches 51 and 52 in the diagram are indicative of the relation of the conductor 39 with the drum 41, designated 41' in the diagram.

A second make and break device is operably connected with a countershaft 23, and comprises a drum 53 having flanges 54 and 55, the latter having a contact lug 56, there

being a contact spring 57 constantly engaging the flange 54 and a contact spring 58 adapted to form electrical connection with the lug 56 periodically as the drum is rotated. These contact spring are mounted on 70 corresponding posts 59 and 60 and are electrically connected by means of conductors 61 and 62 with such other electrically operated and controlled apparatus (not shown) as may be desired and which forms 75 no part of the present invention.

It is the intention that the shunt switch 50 may be either manually operated, or momentarily closed by any suitable automatic mechanism (not shown), such as 80 a clock arranged in the usual way to close an electrical circuit at predetermined periods. When the switch 50 is closed, current is supplied from the source of energy 38 to the motor 16 so that movement is imparted to the mechanism connected therewith. In this manner the main shaft 3 together with the drums thereon are caused to revolve, the hammers being respectively actuated as they are engaged by the projecting lugs on the corresponding drums in the sequence of their arrangement thereon. Also, the drums 41 and 53 are caused to revolve as the countershaft 23 is rotated so that the notch 44 in the flange 43 passes 95 the spring 46 when contact of the spring with the flange establishes a closed circuit through the conductor 39, maintaining a connection for the supply of current to the motor, though the shunt switch 50 be re-opened, until the spring 46 again enters the notch 44 and thus breaks the circuit, at which time the motor and gearing driven thereby ceases operation. Thus, it will appear that the supply of current to the motor is established when the shunt switch is closed, and that the supply is maintained through the make and break device until the gear mechanism completes its cycle of movement and the spring 46 of the make 105 and break device re-enters the notch 44 and thereby breaks the circuit through which the current to the motor is supplied.

By connecting the conductors 61 and 62 in a circuit controlling electrical apparatus 115 apart from the present invention, the same may be caused to periodically function as the drum 53 rotates and the circuit through the conductors is closed by the contact of the spring 58 and the lug 56.

What I claim is:—

1. In striking apparatus for chimes, a main shaft; a motor actuated gearing adapted to impart rotating movement to the main shaft; a mechanism in operable relation with the shaft adapted to impart thereto endwise reciprocating movement; a series of drums fixed on the main shaft, each drum having a series of projecting lugs arranged in a spiral path thereon; a 120

- series of chime members; a series of trip hammers arranged respectively to have striking relation with the chimes correspondingly and to be actuated separately by the corresponding drums; an electrical make and break device actuated by the mechanism and having connection with the motor for controlling the same and a switch controlled shunt for controlling the motor independently of said make and break device. 5
2. In chimes striking apparatus, a series of chime members; a series of trip hammers for said chimes; an actuating member having a separate group of projecting lugs arranged in a spiral series for each hammer; means for imparting rotary movement to the actuating member; and mechanism adapted to impart lengthwise reciprocating movement to said actuating member. 10
3. In chimes striking apparatus, a series of chime members; a corresponding series of trip hammers therefor; an actuating member for each hammer; means for imparting rotary movement to the actuating member; a rotary bearing device axially aligned with the actuating member; a back gearing driven by the actuating member and having operable relation with the bearing member; a spiral cam on the actuating member engaging the bearing member and operable to move said operating member 15
- longitudinally; and a tension device acting against the actuating member so as to hold the cam in constant contact with the bearing member. 35
4. In striking apparatus for chimes, a main shaft having longitudinal and rotary movement; a series of drums fixed on the shaft, each drum having a series of projecting lugs spirally arranged thereon; a series of chime members; a series of trip hammers arranged respectively in striking relation with the corresponding chimes and actuated respectively by the lugs on the corresponding drums; electrically actuated driving means for the main shaft; and an electrical make and break device having actuated relation with the main shaft and adapted to control the driving means. 40
5. In apparatus of the class described, a series of chime members; striking members for the respective chime members; an actuating member; engaging means on the actuating member for the respective striking members; driving means for the actuating member; and mechanism for imparting rotary and longitudinal movement to said actuating member. 45

In testimony whereof I affix my signature.

GEORGE L. SMITH.
